UNITED STATES PATENT OFFICE.

PARVIN WRIGHT, OF CHICAGO, ILLINOIS.

WIRE DRAWING AND SWAGING MACHINE.

Application filed July 13, 1923. Serial No. 651,256.

To all whom it may concern:

Be it known that I, PARVIN WRIGHT, a citizen of the United States, residing at Chicago, in the county of Cook and State of Illinois, have invented certain new and useful Improvements in Wire Drawing and Swaging Machines; and I do hereby declare the following to be a full, clear, and exact description of the invention, such as will 10 enable others skilled in the art to which it appertains to make and use the same.

This invention relates to machines for drawing wire from rods and swaging the drawn wire into predetermined forms while straightening and cutting the same into predetermined lengths and depositing the cut wires into piles at the end of the machine all in a single operation. It has for its object to improve the mechanisms and operations heretofore proposed, as well as to provide a machine which will be simple in construction and more efficient in action than those heretofore known.

With these and other objects in view, the invention consists in the novel details of construction and combinations of parts more fully hereinafter disclosed and particularly pointed out in the claims.

Referring to the accompanying drawings forming a part of this specification in which like numerals designate like parts in all the views:

Figures 1 and 1^a constitute a longitudinal, sectional elevation of a machine made in accordance with this invention, as viewed on the line 1—1 of Figures 2 and 2^a;

Figures 2 and 2^a constitute a top plan view of the parts shown in Figures 1 and 1^a;

Figure 3 is a side elevational view partially in section of the "gypsy head" portion of the machine illustrating the initial bending of the wire around the pulling drum and the use of the gripping means;

Figure 4 is a sectional view taken on the line 4—4 of Figure 3, looking in the direction of the arrows;

Figure 5 is a sectional view of a portion of the parts shown in Figure 4, and illustrating the manual means for raising and lowering the lower die roller;

Figures 6 and 7 are detailed sectional views illustrating the reducing dies;

Figure 8 is a detailed view partially in section of the straightening rolls with the wire in position;

Figure 9 is a sectional view taken on the line 9—9 of Figure 2^a, showing the swaging and cutting dies and their associated parts;

Figure 10 is a sectional detailed view taken on the line 10—10 of Figure 2^a, looking in the direction of the arrows;

Figure 11 is a sectional detailed view taken on the line 11—11 of Figure 2^a, looking in the direction of the arrows; and

Figure 12 is a detailed perspective view of the finished wire product swaged and cut to a predetermined length.

In order that the precise invention may be the more clearly understood, it is said: As is well known, there is now a very considerable commercial demand for wires of a predetermined size cut into predetermined lengths of say from four to fifteen feet and having deformed ends, which are used for banding boxes and other packages under tension.

That is to say, these said wires are employed in special machines which after the wires have been wrapped around the box to be banded puts said wires under tension and twists parallel bights of the wire together into a knot, after which the ends of the bights are cut off and the box is effectually sealed as well as protected from breakage during shipment.

These wires must be shipped to the users in the form of straight lengths or rods of similar diameter, and in packages of a predetermined number, say two hundred and fifty.

At present, in order to form these straight wire lengths, having deformed ends, a number of operations are necessary to be carried out. That is to say, prior to this invention, the original wire has been drawn from the rod and made into coils at a wire mill, which we may call the first operation. The finished coils are then piled up, and are loaded into cars, which we may call the second operation. The loaded cars carry the finished coils to some distant plant where they are unloaded which we may call the third operation. The unloaded coils are next passed through straightening machines, in order to get the kink or curva-

ture out of the wires, and they are then cut into predetermined lengths and prepared for reshipping which we may call the fourth operation.

According to this invention, on the other hand, the wire is made directly from the mill rods, straightened, swaged or fabricated, all in one continuous operation, thus eliminating the expenditure of a great deal of time and of money, which has been heretofore found to be necessary. An important feature of this invention resides in the employment of what I call a "gypsy head" drum in the drawing machine, by which the drawing of the wire is accomplished without producing an undue amount of slack in the wire, thus avoiding the breaking of the latter between the reducing dies. Other features of the invention will appear in what follows, but it might be remarked that the machine is so constructed as to permit both sides thereof to be provided with drawing members, thus doubling the capacity the machine would have if only one side were used.

Referring to the drawings, 1 indicates any suitable framework, 2 a motor provided with a drive shaft 3, located centrally of the framework, and provided with the worms 4, 5, 6 and 7 respectively meshing into the worm gears 8, 9, 10, and 11 to which the so-called "gypsy head" drums 12, 13, 14, and 15 are respectively connected by means of the shafts respectively numbered 16, 17, 18, and 19, all of which will be clear from Figures 1, 1^a, 2 and 2^a. The said shafts 16, 17, 18, and 19 respectively turn in bearings 20, 21, 22 and 23 as best shown in Figures 2 and 2^a, and on the ends of said shafts opposite to those of the gypsy drums mentioned are respectively attached companion gypsy drums 24, 25, 26 and 27, as will be clear from the drawings. The worms and gears 4 and 8, 5 and 9, 6 and 10, and 7 and 11 are all of a different pitch, so that the speed of each succeeding worm and gear increases over the speed of the preceding worm and gear. That is, the worms and gears 4 and 8 will have the slowest speed, while the worms and gear 5 and 9 will have a speed of about double that of 4 and 8. The worm and gear 6 and 10 will have a speed of about double that of 5 and 9, and the speed of the worm and gear 7 and 11 will be about twice the speed of the worm and gear 6 and 10. As a consequence of these successive increases in speed the shafts 16, 17, 18 and 19 will have a successively greater speed and the pairs of gypsy drums 12, 24, 13 and 25, 14 and 26, and 15 and 27 will have successively greater speeds. Of course, the actual speeds that are employed will depend upon the particular wire that it is desired to produce, but the above ratios will give an ap-

proximate idea of the speeds that are to be employed in this machine. The rod to be formed into wire is indicated by the numeral 34 and it passes between successive pairs of reducing dies at each gypsy head and around each gypsy head or drum, as will presently be disclosed.

These said roller dies of course increase the length of the rod, and the increased travel of each succeeding gypsy head or drum such as 12 and 13, and 14, etc., partly compensates for this said increase in length. But it is not necessary that the speed of the drums should absolutely compensate for the lengthening of the wire, because each gypsy head or drum automatically regulates the speed of travel of the wire in such a manner as will compensate for any differences in length, as will be more fully explained hereinafter. As roller dies reduce the rods much easier and with considerable less power than block dies, up to the finished operation, I provide a sufficient number of roller dies to bring the wire to the approximate diameter desired, and then pass the almost finished wire through one or more block dies to reduce it to its final diameter.

Referring more particularly to Figure 3, the supporting frame 1 is provided with a bracket or support 29 on which is pivoted as at 30 the lever like plate 31 provided with the adjusting screw 32 controlled by the spring 33. This plate 31 is provided with a plurality of vertically disposed extensions 39 in which are mounted the shafts 35 and 36. The shaft 35 is provided with an eccentric 37 on which is mounted the lower roller die or roll 44, and on the shaft 36 is mounted the upper roller die or roll 43. The handle 45 is rigid with the shaft 35, and therefore is capable of swinging the eccentric 37 and the roller die or roll 44 around the center of shaft 35, while the adjusting screw 32 enables one to still further adjust the space between the two dies 43 and 44 by bodily moving said shaft 35 and eccentric 37. Since the roller dies like the gypsy heads and other mechanism are duplicated on each side of the machine, the same reference numerals are applied to like parts on both sides of the machine. Therefore, referring to Figure 4, which shows the dispositions of the parts of the machine on the side opposite from that shown in Figure 3, it will be observed that the uprights 39 are three in number, and that the lever 45 is disposed between two of them, while the roller dies or rolls 43 and 44 are on the outside of said uprights. Further, disposed between a pair of said uprights 39 is the friction disk 52, rigid with the shaft 36 and die 43. This said disk frictionally engages the friction disk 51 rigid with the shaft 16 driven by the worm gear 8 meshing with the worm 4 driven by the power shaft 3. It will further be

observed that the said friction disk 52 being mounted upon the extension 39 turns around the point 30 as a pivot, and thus can be moved toward and from the friction disk 51 5 against the compression or tension of the spring 33 as the case may be. In so far as the mechanism has now been disclosed it will be understood that the lever 45 may be readily manipulated to increase the opening 10 between the dies 43 and 44, so as to admit the rod 34, whereupon a turning of the power shaft 3 and friction disk 51 will through friction turn the friction disk 52 and the roller dies 43 and 44 to such an extent as to 15 reduce a portion of the end of the rod 34. This reduced end is conveniently gripped by the sleeve 40 provided with the clamping lever 41 and with the flexible connection 42 having the hook 28 adapted to engage in one 20 of the holes 46 with which the friction disk 51 is provided. Therefore, it follows that if power is now continuously applied to the said friction disk 51 in the manner above disclosed, the rod 34 will be forcibly drawn 25 between the reducing dies 43 and 44, and its reduced end will be wrapped around the gypsy head or drum 12 in place of the flexible connection 42. In like manner, the reduced end of the rod is led to the next pair 30 of roller dies associated with the drum or gypsy head 13, wrapped around said drum and then led to the next pair of reducing dies associated with the gypsy head 14, and so on until it reaches the block die to be 35 described hereinafter.

During this operation, each of the levers 45 may not be thrown back to the normal position, if it is desired to make the threading of the rod 34 between the dies easier. 40 On the other hand, after the rod 34 has been properly threaded through the various dies each of the levers 45 associated with their respective pairs of roller dies 43 and 44 are thrown back to their normal positions, 45 whereupon the openings between the roller dies are closed to the size to which it is desired to reduce the wires at the pairs of dies in question. The continued application of power through the shaft 3 and respective 50 worms 4, 5, 6 etc., will now cause each of the drums 12, 13, 14, etc., to pull on the partially formed wire which is wrapped around the same, and thus will each friction disk 52 be turned around the center point 30 against 55 the compression of the spring 33 to increase the driving friction between the disks 51 and 52. That is to say, the harder the pull or the more reduction that is required in the wire at each drum head 12, 13, 14, etc., the 60 greater will be the friction between the driving disk 51 and the driven disk 52. That is, the pull of the wire itself governs the amount of power that is applied to the rotation of the reducing roller dies.

65 Now, it will be apparent that if the re-

duction of the wire or rod 34 at any particular pair of dies causes the wire to lengthen to a degree which cannot be taken care of by the increased speed at which the corresponding gypsy head drum 12, 13, 14, etc., is 70 rotated, then the friction of the said reduced wire around the drum in question will lessen, which in turn will lessen the pull on the corresponding roller die 43 and friction disk 52, and thus will the feed of 75 the wire 102, at the particular gypsy drum in question, be lessened.

It thus results that each of the drums 12, 13, 14, etc., automatically governs the speed of the wire through their corresponding 80 reducing dies, and takes care of any excess of length that would otherwise occur. In the same way, should the feed of the rod 34 between any given pair of dies 43, 44 be insufficient then the friction of the reduced 85 wire around the corresponding gypsy drum 12, 13, 14, would be increased, and the power applied to the corresponding reducing dies 33 and 34 would be likewise increased, so that the speed of the wire between the dies 90 would be in turn increased. So again, it is apparent that no matter whether too much wire is fed to a given drum 12, 13, etc., or too little wire is fed thereto, the action of these drums is perfectly automatic to maintain the 95 speed of the wire through the dies at a predetermined point. Of course, it will be understood that each friction disk 51 is rigid with its corresponding gypsy drum 12, 13, 14, etc.

100 Further, it will be apparent that the actual speed at which the wire travels through the dies will not only be governed by the gear ratios between the power shaft 3 and the various driven worm gears 8, 9, 10, etc., but 105 would also be governed in a measure by the adjustment of the screws 32 and the compressions of the various springs 33. The wire before being thus reduced to the approximate size by means of the roller dies just 110 described, has been, however, passed on through one or more block dies 53 as above intimated. Ordinarily one block die will be sufficient, and it is composed of a lower half 55, see Figures 6 and 7, and an upper 115 half 56. 58 represents a lever provided with a cam 57 to control the movements of the upper half 56 and to thus enable the wire to be inserted and the end attached to the drum 15, see Figure 1^a. This attachment, of course, to the drum 15, is similar to that of the preceding gypsy drums and takes place before the roller dies have 120 commenced to work. From the drum 15 the wire passes on through the straightening 125 machine 100 and thence through the swaging machine 101 to be presently described. As above stated, this threading of the wire all takes place before the roller dies have 130 commenced to operate on the finished wire.

On the extreme right hand end of the motor shaft 3 as seen in Figures 1^a and 9, is a driving worm 61 meshing with a worm gear 62 mounted on the shaft 63. Said shaft 63 also carries an intermediate gear, not shown, but which is rigid with and is located behind gear 62, as seen in Fig. 1^a, and this intermediate gear meshes with a gear 64, mounted on the shaft 65 provided with 10 a pinion 66 meshing with the gear 67, mounted on the shaft 68, rigid with a pinion 69 meshing with the gear 70, mounted on the shaft 71, rigid with the pinion 72, meshing with the pinion 73, mounted on the 15 shaft 74. As best shown in Figure 9, the shaft 65 carries a roll 75 coacting with the roll 76 mounted on the shaft 77, carried by the frame 78 pivoted at 79. Further, the shaft 71 carries the cutting and swaging die 82, coacting with the cutting and swaging die 83 mounted on the shaft 74 carried by the vertically adjustable frame member 81.

The wire 102 after passing through the straightening machine 100 provided with the straightening rollers 103, 104, and 105, passes on between the feed rollers 75, and 76, driven from the shaft 65 and between the 20 swaging and cutting dies 82 and 83 as illustrated.

The shaft 65 is the main driving shaft of the parts of the machine 101 and is supported in the framework 105' mounted on the main frame 1 of the apparatus.

As best shown in Figure 2^a, there are two frames 105' mounted on the main frame 1, and the gears and coacting parts numbered from 66 to 83 above mentioned are duplicated on each side of the main supporting frame as are the gypsy drums and other parts above disclosed. That is, the mechanisms are duplicated on each side of the main driving shaft 3 throughout this machine.

It will be observed that the upper feed roll 76 being mounted on the frame 78, its feeding action is controlled by the screw 106 and the compression of spring 107. 108 is a screw carried by the end of frame 78, and the lower end 109 of this screw rests on 50 the squared surface of the member 110 pivoted as at 111. Rigid with the member 110 is the lever 112 provided with the roller 113 adapted to be struck by the cam 114 with which the cutting and swaging die 83 is provided. When said roller is thus struck by said cam it slightly raises or turns the member 110 on its pivot and through the screw 108 and member 78 slightly raises the feed roller 76 from its contact with the driven roller 75 and momentarily stops the pull of the wire through the straightening machine 100. The member 78 also has pivoted thereto as at 115 the lever 116 whose lower end rests on the surface 117 of the 60 frame 105'. Should the operator at any

time wish to stop the feed of the wire through the machine 101 he can do so by turning this lever toward the left as seen in Figure 9.

The swaging rollers 82 and 83 are provided with swaging dies 119 and cutters 120, which deform the ends of the finished wire ends 123, as indicated at 121, and cuts said wires into lengths as indicated at 122.

The operation of this machine will be clear from the foregoing, but may be briefly summarized as follows: The various gypsy heads or pulling drums 12, and 24, 13 and 25, 14 and 26, and 15 and 27 are operated at successively greater speeds through the gear ratios adopted between the worms 4, 5, 6, etc., and their corresponding worm gears 8, 9, 10, etc. Further, rigid with said pulling drums are the friction disks 51 which drive friction disks 52 which are rigid with the upper roller dies 43 as illustrated. But the said upper rollers dies 43 and their coacting lower roller dies 44 are pivoted on frame extensions 39, to swing around the pivotal points 30 of the various plates levers 31, with which each pair of roller dies 43 and 44 are associated.

It thus results that when the partially drawn wire 34 is pulled through a given pair of roller dies 43 and 44, the pulley of said partially drawn wire governs the friction between the disks 51 and 52, and thus governs the power with which the upper rollers die 43 is driven. The power with which the said upper roller die is driven in each case, of course, governs the speed with which the partially drawn wire 34 is fed to a particular pulling drum. Therefore, if the wire becomes too much elongated at any stage of the operation, the friction around a given drum 12 will be lessened, the pull will be lessened, the driving power from the friction disk 51 will be lessened, and the slack will be immediately taken up. On the other hand, should the elongation of the wire through any particular pair of roller dies 43 and 44 be insufficient to meet the desired requirements, then the pull on the corresponding upper die 43 will be increased, the friction between the driving disk 51 and the driven disk 52 will be increased, and consequently the feed through the particular pair of roller dies 43 and 44 will be increased, so that there is an automatic tendency to take care of the elongation of the wire throughout the machine, and to cause a smooth and continuous operation of the same.

It thus results that the various lengths to which the wires are elongated after passing through any particular pair of roller dies are automatically governed and that the wire is continuously fed to the block dies 53 and is continuously drawn through said block dies by the pulling

drums or gypsy heads 15 and 27, as will be readily understood. From these said drums 15 and 27 the wire is continuously fed to the straightening machines 100. It requires of course a considerable power to draw the wire through a straightening machine and this power is supplied by the pulling or feeding drums 75 and 76, see Figure 9. It therefore results that in the operation of this machine the rods are fed in at one end and the finished wire 102 is continuously fed to the straightening machines as above disclosed, while the feeding or pulling rolls 75 and 76 draw said wire through said straightening machines and pass it on to the swaging and cutting rolls 82 and 83. Now the speed of the feed rolls and the diameters of the swaging and cutting rolls determines the lengths into which the wire are finally cut, as will be readily understood. But it is desirable, although not necessary, to have a slight and momentary pause of the wire during the cutting action. To accomplish this, the swaging roll 83 is provided with a cam 114 which strikes the roller 113, moves the lever extension 112 toward the left as seen in Figure 9, and thus slightly raises the block 110 on its pivot 111, and thus raises the screw 108, the frame 78, and the feed roller 76, and consequently momentarily stops the feed of the wire at the moment of the swaging and cutting action. While this temporary stoppage of the feed of the wire is had, the fed wire will slightly bend before the straightening machine as indicated at 126 in Figure 8. The pause of the movement of the wire is so very slight, this said slack or bend 126 is immediately taken up by the feed rolls 75 and 76, and the cutting and swaging action continues.

Of course, it will be understood that whereas it is desirable to deform the ends of the cut lengths 127, yet it is not absolutely necessary to do so, for said lengths 127 can be cut just as well without employing the swaging dies, and therefore this invention is intended to cover a machine for drawing and cutting the wires, as well as a machine for drawing, swaging and cutting the wires.

It will now be clear that by simultaneously drawing, straightening, swaging and cutting the wires, the operator avoids the annoyance and the expense which has heretofore been entailed due to the finished coils of the wire becoming entangled when being fed to the straightening machines, as well as the delay and expense which is entailed in the manufacture of the finished coils of wire at one place and the cutting and swaging of the wires at another place. By this invention the entire operation of converting a mill rod into finished straight wires of predetermined lengths is accomplished all in a single opera-

tion. In other words, the successful operation of the feeding rolls 75, and 76 as well as of the swaging rolls 82 and 83 is dependent upon the continuous and smooth feeding of the wire 34 to the straightening machines 100 and to the synchronism of all the driving parts due to their connections with the single driving shaft 3. The length of the straightened swaged wires 127 is best controlled by the reducing gears lettered from 67 to 70. These said gears, as will be clear from Figure 1st, are carried on the lever 130 playing over the rack 131, and may therefore be readily lifted off the machine and other gears of other dimensions substituted therefor. By this means the speed of the swaging and cutting wires is governed and the lengths of the cut wires correspondingly changed. Of course it will be understood that all the mechanism above described is duplicated on each side of the machine.

It is obvious that those skilled in the art may vary the details of construction as well as the arrangement of parts without departing from the spirit of the invention, and therefore I do not wish to be limited to the above disclosure except as may be required by the claims.

What is claimed is:

1. In a combined wire drawing and cutting machine, the combination of means for drawing the wire to a predetermined size; means for straightening the drawn wire during the drawing operation comprising means for pulling the drawn wire through the straightening machine; and means for cutting a portion of the straightened wire in predetermined lengths while another portion thereof is being fed to said straightening machine.

2. In a combined machine for drawing and cutting wire, the combination of a plurality of dies through which the wire is drawn; a straightening means to which the wire directly passes from said dies; means to pull said drawn wire through said straightening machine; means to cut into predetermined lengths the straightened wire; and means to stop the pulling action during the cutting operation.

3. In a combined machine for drawing, straightening, and cutting wire, the combination of a plurality of drawing dies; means to pull the wire through said dies; means to regulate the length of the wire passing said dies by the pull of the same on the dies; a straightening machine to which the regulated lengths of wire are continuously passed from said dies; means to intermittently at regular intervals pull the said regulated lengths of wire through said straightening machine; and means for cutting said wire into predetermined lengths between said intervals.

4. In a combined machine for drawing,

straightening, swaging and cutting wire, the combination of a plurality of reducing dies; means to pull the reduced wire through said dies; means to regulate the lengths of wire reduced in said dies by the pull of the said wire on individual dies; a straightening machine to which the reduced wire is continuously fed from said dies; feeding means for pulling the reduced wire through said straightening machine for predetermined intervals; means to swage and cut the pulled wire between said intervals; and means for operating the dies, the pulling means, the feeding means and the swaging and cutting means in synchronism with each other.

5 5. In a wire drawing machine, the combination of a plurality of roller dies; means for pulling the wire through said dies; means for regulating the lengths of wire reduced at each die by the pull of the wire at each die; and means for simultaneously swaging and cutting into predetermined lengths the said wire after passing said dies.

25 6. In a wire drawing machine, the combination of a plurality of roller dies; power driven means for pulling the wire through said dies; friction driven means for regulating the lengths of wire reduced at each die by the pull of the wire at each die; and means to simultaneously swage and cut into predetermined lengths the said wire after passing said dies.

35 7. In a wire drawing machine, the combination of a plurality of roller dies; means for pulling the wire through said dies comprising a power driven rotating drum around which the wire is passed; and means for regulating the lengths of wire reduced at each die by the pull of the wire at each die comprising a pivoted disk frictionally driven from a member rigid with said drum.

45 8. In a wire drawing machine, the combination of a plurality of pairs of roller dies; means to permit said pairs of dies to move around a fixed center; means to frictionally drive one of the dies in each pair; and a drum associated with each pair rigid with said last named means adapted to

50 pull the wire through its corresponding pair of dies.

9. In a wire drawing machine, the combination of a plurality of pairs of roller dies; means to permit said pairs of dies to move 55 around a fixed center; means to control the amount of power required to move said dies around said center; means to frictionally drive one of the dies in each pair; a drum associated with each pair rigid with 60 said last named means adapted to pull the wire through its corresponding pair of dies; and means to drive said dies and drums in synchronism and at different speeds.

10. In a combined machine, the combination of a power shaft; a plurality of pairs of wire drawing dies disposed on each side of said shaft; a drum for each pair of dies adapted to pull the drawn wire through 65 its corresponding pair of dies; means for pivotally mounting each pair of dies to enable the pull of its corresponding drum to move said dies around a fixed center; means associated with said drums for frictionally driving one of the dies of each pair; and friction means moving with each pair of dies adapted to be driven from each drum.

11. In a combined machine, the combination of a power shaft; a plurality of pairs of wire drawing dies disposed on each side of said shaft; a drum for each pair of dies adapted to pull the drawn wire through 70 its corresponding pair of dies; means for pivotally mounting each pair of dies to enable the pull of its corresponding drum to move said dies around a fixed center; means associated with said drums for frictionally driving one of the dies of each pair; friction means moving with each pair of dies adapted to be driven from each drum; a wire straightening machine on each side of said shaft to which the reduced wire passes from said dies; means on each side of said shaft for pulling the wire through said straightening machines; and means on each side of said shaft for cutting the wire into predetermined lengths.

40 In testimony whereof I affix my signature.

PARVIN WRIGHT.
